(57) **CLAIM**

The ornamental design for a fish feeding apparatus, as shown and described.

DESCRIPTION

FIG. 1 is a perspective view of a first embodiment of a fish feeding apparatus.

FIG. 2 is a front side view of the fish feeding apparatus of FIG. 1.

FIG. 3 is a right side view of the fish feeding apparatus of FIG. 1.

FIG. 4 is a top view of the fish feeding apparatus of FIG. 1.

FIG. 5 is a bottom view of the fish feeding apparatus of FIG. 1.

FIG. 6 is a an exploded of the fish feeding apparatus of FIG. 1.

FIG. 7 is a top perspective view of the tubular member of the fish feeding apparatus, shown separately for clarity.

FIG. 8 is a side view of the of the tubular member of FIG. 7.

FIG. 9 is a top of the tubular member of FIG. 7.

FIG. 10 is a bottom view of the tubular member of FIG. 7.

FIG. 11 is a top perspective view of the insert of the fish feeding apparatus, shown separately for clarity.

FIG. 12 is a front side view of the of the insert of FIG. 11.

FIG. 13 is a right side view of the of the insert of FIG. 11.

FIG. 14 is a top view of the of the insert of FIG. 11.

FIG. 15 is a bottom view of the of the insert of FIG. 11.

FIG. 16 is a perspective view of the feeding tray of the fish feeding apparatus, shown separately for clarity.

FIG. 17 is a front side view of the feeding tray of FIG. 16.

FIG. 18 is a top view of the feeding tray of FIG. 16; and, FIG. 19 is a bottom view of the feeding tray of FIG. 16.

The broken lines in the figures show portions illustrating environmental structures that form no part of the claimed design.
